UNITED STATES PATENT OFFICE

108,899

DESIGN FOR A PENCIL

Glenn W. Tammen, Chicago, and Hudson B. Roysher, Champaign, Ill., assignors to Auto-point Company, Chicago, Ill., a corporation of Illinois

Application January 12, 1938, Serial No. 74,223

Term of patent 7 years

To all whom it may concern:

Be it known that we, Glenn W. Tammen and Hudson B. Roysher, citizens of the United States, residing at Chicago, in the county of Cook and State of Illinois, and Champaign, in the county of Champaign and State of Illinois, respectively, have invented a new, original, and ornamental Design for a Pencil, of which the following is a specification, reference being had to the accompanying drawing forming a part thereof.

In the drawing:

Fig. 1 is a side elevation of a pencil showing our design.

Fig. 2 is a view similar to Fig. 1 but showing the pencil rotated through 90° and looking directly toward the clip.

Fig. 3 is a plan view looking at the upper end of Fig. 1.

We claim:

The ornamental design for a pencil substantially as shown and described.

GLENN W. TAMMEN.
HUDSON B. ROYSHER.
